[57] CLAIM

The ornamental design for a gun safety shield, as shown and described.

DESCRIPTION

FIG. 1 is a perspective view of a gun safety shield according to this invention;

FIG. 2 is a left side view thereof;

FIG. 3 is a right side view thereof;

FIG. 4 is a top view thereof;

FIG. 5 is a bottom view thereof;

FIG. 6 is a front view thereof;

FIG. 7 is a back view thereof;

FIG. 8 is a perspective view of another embodiment of the gun safety shield;

FIG. 9 is a right side view thereof;

FIG. 10 is a left side view thereof;

FIG. 11 is a top view thereof;

FIG. 12 is a bottom view thereof;

FIG. 13 is a back view thereof; and,

FIG. 14 is a front view thereof.

The broken lines are for the purpose of illustrating the environment of use and form no part of the invention.
